CLAIM

The ornamental design for a wearable electronic device, as shown and described.

DESCRIPTION

FIG. 1 is a perspective view of a wearable electronic device, showing our new design;

FIG. 2 is a front view thereof;

FIG. 3 is a rear view thereof;

FIG. 4 is a side view thereof;

FIG. 5 is another side view thereof;

FIG. 6 is a top plan view thereof;

FIG. 7 is a bottom plan view thereof; and,

(Continued)

FIG. 8 is another perspective view thereof in an alternate configuration.

The broken lines shown in the drawings illustrate portions of the wearable electronic device that form no part of the claimed design.

1 Claim, 8 Drawing Sheets
